Morley, near Leeds, England, assignors of one-
third to Henry Lister & Sons Limited, Pudsey,
Yorkshire, England

Application October 10, 1938, Serial No. 234,308
In Great Britain October 15, 1937

8 Claims. (Cl. 28—19)

This invention relates to apparatus for automatically cleaning or removing the residue of yarn left on a bobbin after discharge from an automatic weft replenishing bobbin-changing loom. The apparatus provided in accordance with this invention may be arranged so as to clean the bobbins as soon as they leave the loom and without damaging the bobbins, which are ready for use again immediately they are delivered by the cleaner. The yarn is not subjected to a stripping action which is likely to tear it to lint form so that the waste yarn is recovered substantially intact. Cleaning by hand or by a separate machine is thus entirely superseded by the use of apparatus of simple construction as hereinafter more particularly described.

The bobbin cleaner according to the present invention consists broadly of means for temporarily arresting the discharge bobbin in its passage through the cleaner, means for unwinding the waste yarn from the bobbin while the latter is thus temporarily arrested and before or while it continues on its discharge movement. Means may be provided for temporarily gripping or holding the loose end of the residue of weft yarn during the unwinding operation.

A preferred embodiment of the invention in the form of an attachment for an automatic bobbin-changing loom (e. g. Northrop loom) is illustrated in the accompanying drawings.

In the drawings:

Fig. 1 is a longitudinal cross-section through the bobbin cleaner.

Figure 2 is a plan view looking in the direction of arrow II of Figure 1.

Figure 3 is a side elevation looking in the direction of arrow III of Figure 2; and,

Figure 4 is a fragmentary side elevation looking in the direction of arrow IV of Figure 2.

The bobbin with the residue of yarn still in position and the yarn end trailing therefrom is received by a chute 1 provided at one end of the casing 2 of the attachment. The attachment is supported by the loom frame in such manner that the bobbin-receiving chute 1 is located so that when the loom sley is in the bobbin-changing position an "empty" bobbin which has been forced through the bottom of the loom shuttle by a full bobbin from the bobbin magazine or battery and which displaces the empty bobbin under the action of the transfer hammer, drops down the discharge chute on the sley into said cleaner chute 1. The bobbin battery, transfer hammer mechanism and bobbin discharge chute of the loom form no part of the present invention and are accordingly not illustrated. The cleaner receiving chute 1 is so shaped as to guide the entering bobbin 3, which normally drops from the shuttle with base downwards, on to an apron conveyor consisting of an endless band 4 of card

clothing extending between a pair of supporting rolls 5 disposed transversely of the casing 2 of the cleaner. The cleaner chute 1 may be made adjustable to ensure correct feeding of the entering bobbin 3 to the conveyor 4. The card-cloth apron 4 is slightly inclined and above its upper end or half is resiliently mounted a member for taking hold of and holding the loose end of the residue of yarn on the bobbin. This yarn-holding member is preferably in the form of a yielding or flexible (e. g. rubber) plate 6, but may consist of a freely revoluble roller covered with card clothing. In addition to being resiliently mounted this yarn-holding member may have an elevating swinging motion imparted to it periodically.

The surface of the apron conveyor 4 may be arranged (for example, by providing one or more gaps 7 or recesses in the card clothing) so as to urge forward the bobbin 3, hitherto riding with in the chute 1 upon the receiving end of the conveyor until the base 8 of the bobbin 3 (which had entered and has now left one of the gaps 7 or recesses in the apron surface) is arrested temporarily by a movable stop 9. At this position 25 of temporary rest the base 8 of the bobbin 3 is situated above the bite of a pair of nipping rolls 10—11, the tops of which are substantially in alignment with the upper surface of the apron 4. These rotating nipping rolls 10—11 entrain 30 the yarn 12 (the loose end of which is held by the card-clothing of the apron 4 on to which it has been pressed by the holder 6) and draw same down between them from off the bobbin 3 as it is leaving the cleaner. The drawn-off yarn is 35 deposited by the nip rollers 10—11 into a suitable receptacle, not shown.

The gripping of the loose end of the yarn 12 by the holder 6 is preferably effected simultaneously with the removal of the stop member 9 to allow the temporarily arrested bobbin 3 to continue its journey. This stop member may be and preferably is in the form of a smaller diameter roller normally resting upon the periphery of the outermost nip roller 11 (i. e. the nip roller 45 nearer the discharge end of the cleaner and remote from the apron conveyor 4). In this case the small bobbin-stop roller 9 and the yarn holder 6 may be mounted on opposite ends of a pivoted frame 13 which is tilted periodically by 50 the engagement of an arm 14 mounted on the spindle 15 of the pivoting frame 13 by means of a cam 16 which is carried on the spindle 17 of one of the rotating apron-supporting rollers 5. As the frame 13 tilts it raises the bobbin stop 55 roller 9 to allow the bobbin 3 to fall through guides 18 into a collecting bin (not shown) and simultaneously lowers the yarn holding member 6 so that the residue of yarn is not allowed to leave the cleaner on the discharging bobbin. 60

The yarn 12 from the bobbin is prevented from wrapping around nip roller 10 by a rubber or cloth-faced metal strip 19 maintained in contact with the periphery of said roller. Brushes 20 for cleaning loose yarn ends from the apron 4 are also provided. The nip roller 11 is rotated by a belt passing around a pulley 21 on the spindle of said roller 11, and this rotary motion is transmitted to the roller 10 and one of the conveyor rollers 5 by means of a pair of toothed gears 22, a chain belt 23 and sprocket wheels 24.

The function of the member 6 is two-fold, namely, to act as a temporary stop to the bobbin when the latter is thrown into the chute, and to press the trailing yarn end into contact with the carded conveyor 4. The sequence of operations is as follows: The bobbin is ejected by known means from the bottomless shuttle in the loom and drops into the chute of the apparatus. Since the plate 6 and roller 9 are supported by the opposite ends of rocker 13 one is raised while the other is lowered, so that when the plate 6 is lifted it allows any bobbin resting in the chute to drop down into contact with the carded conveyor 4, whereby the bobbin 3 is carried forward until arrested by the lowered roller 9, the loose end of the waste yarn on the bobbin 3 trailing along the conveyor 4. When, by reason of cam 16 operating the rocker 13, the roller 9 is lifted to allow the bobbin 3 to leave the apparatus, the plate 6 is simultaneously lowered, thereby pressing the trailing yarn into contact with the conveyor 4. The points or needles of the carded material cause the yarn to adhere to the conveyor 4 to prevent the bobbin 2 carrying all the waste yarn with it. The primary function of the plate 6 is, therefore, to press the yarn end into adhering contact with the conveyor surface, although it plays some part in preventing the yarn end passing out of the apparatus with the bobbin. Actually the member 6 would be made of a material suited to the yarn dealt with, and in some cases may be provided with a carded surface. The discharged bobbin 3 may carry some yarn with it, but the grip of the carded conveyor 4 is sufficient to hold the yarn so that the bobbin 3 generally spins round in order to free itself from the held yarn. As the bobbin passes over and beyond the roller 11 the upper portion of said roller 11 (which moves in a direction counter to the direction of advance of the yarn by the conveyor 4) resists advance of the yarn thereover and, in fact, acts to move the yarn in a direction counter to the direction in which its trailing end portion is advanced by the conveyor 4. As a consequence there is formed in the yarn, between the conveyor 4 and the roller 11, a loop which is caused by the rollers 10 and 11 to be carried between said rollers and thereby be pulled from the conveyor 4 and the bobbin and to be discharged beneath said rollers.

On some occasions the rollers 10, 11 deal with the yarn entirely before the bobbin leaves the apparatus, and on other occasions the portion of yarn carried away with the bobbin is drawn back by the rollers 10, 11.

The frame 13 is resiliently mounted by connecting a tension spring 25 to an arm 26 secured to the frame spindle 15.

We claim:

1. Apparatus for automatically cleaning or removing the residue of yarn left on a bobbin after discharge from an automatic weft-replenishing bobbin-changing loom, comprising, a cleaner receiving chute into which the yarn

carrying bobbin falls and is discharged base foremost, an endless web for receiving the bobbin, a pair of oppositely rotating rolls adjacent the discharge end of the said web, a cam actuated rock shaft, arms extending in opposite directions substantially radially of said shaft, a stop member carried by one of said arms and in engagement with the last one of the pair of rolls for temporarily arresting the movement of the bobbin by engaging the base thereof, yarn gripping means carried by the other of said arms and adapted to be moved down into engagement with the surface of the web to grip the trailing yarn as said stop member is lifted and said bobbin is discharged from the apparatus, the loose yarn unwound from the bobbin in the zone of said rolls being gripped thereby and completely pulled from the bobbin and also pulled therethrough from the web.

2. Apparatus for automatically cleaning or removing the residue of yarn left on a bobbin after discharge from an automatic weft-replenishing bobbin-changing loom, comprising stop means movable into and out of the path of a discharged bobbin for temporarily arresting and then releasing the discharged bobbin in its passage through the cleaner, mechanically driven nip rollers for entraining the waste yarn from the bobbin, while the latter is thus temporarily arrested, so as to unwind the yarn from the bobbin, and means movable to temporarily grip and hold and then release the loose or trailing end of the residue of weft yarn during the unwinding operation.

3. Bobbin-cleaning apparatus according to claim 2, wherein the means for temporarily gripping or holding the loose end of the residue of weft yarn comprises a moving gripping surface on to which the yarn end is pressed by a yielding yarn holder.

4. Bobbin-cleaning apparatus according to claim 2, including means whereby the yarn gripping means is actuated to grip the loose yarn end simultaneously with release of the stop means which temporarily arrests the movement of the bobbin.

5. Bobbin-cleaning apparatus according to claim 2, wherein the stop means is in the form of a roller resting upon the outermost nip roller.

6. Bobbin-cleaning apparatus according to claim 2, characterized in that the means for temporarily gripping and holding the end of the yarn includes a flexible plate and conveyor apron covered with card-clothing.

7. Bobbin-cleaning apparatus according to claim 2, wherein the bobbin stop means and the yarn gripping and holding means are mounted on opposite ends of a periodically tilted pivoted frame.

8. Apparatus for automatically cleaning or removing the residue of yarn left on a bobbin after discharge from an automatic weft-replenishing bobbin-changing loom, including a pair of oppositely rotating rolls, conveyor belt means for feeding a bobbin lengthwise across the rolls, means for guiding the discharged bobbin from the loom to said conveyor means, and means for temporarily arresting the passage of the bobbin through the apparatus at the location of said rolls whereby loose yarn unwound from the bobbin and accumulating on said rolls is gripped by the latter and fed to waste between the same.
